(57) **CLAIM**

The ornamental design for a weight training device, as shown and described.

DESCRIPTION

FIG. 1 is a perspective view of a first embodiment of a weight training device showing my new design;

FIG. 2 is a front view of the weight training device in FIG. 1;
FIG. 3 is a rear view of the weight training device in FIG. 1;
FIG. 4 is a left side view of the weight training device in FIG. 1;

FIG. 5 is a right side view of the weight training device in FIG. 1;

FIG. 6 is a top view of the weight training device in FIG. 1;
FIG. 7 is a bottom view of the weight training device in FIG. 1;

FIG. 8 is a perspective view of a second embodiment of a weight training device showing my new design;

FIG. 9 is a front view of the weight training device in FIG. 8;
FIG. 10 is a rear view of the weight training device in FIG. 8;
FIG. 11 is a left side view of the weight training device in FIG. 8;

FIG. 12 is a right side view of the weight training device in FIG. 8;

FIG. 13 is a top view of the weight training device in FIG. 8;
and,
FIG. 14 is a bottom view of the weight training device in FIG. 8.

The broken lines illustrate environmental structure and form no part of the claimed design.
